ADJUSTABLE SECTOR PLATE

Ernest A. Lundstrom, Wellsville, N. Y., assignor
to The Air Preheater Corporation, New York,
N. Y.

Application June 9, 1942, Serial No. 446,351

5 Claims. (Cl. 257—6)

This invention relates to heat exchange apparatus and particularly to improvements in rotary, regenerative air preheaters employed in conjunction with furnaces fired with pulverized coal.

The proper combustion of pulverized coal mined in certain localities is difficult because of its high moisture content. Therefore, it is desirable to utilize primary air of very high temperatures so as to provide sufficient heat for thoroughly drying the coal. The complete combustion of the fuel also requires secondary air, and a rotary air preheater constructed to provide a supply of very hot primary air and also heated, but relatively cooler, secondary air is disclosed in the copending application of Roland S. Cooper filed November 9, 1940, under Serial No. 364,969. This preheater has a "sector plate" at the air outlet end formed with a special opening for primary air as well as the usual opening for secondary air, both being aligned with the air passage through the preheater with the primary air opening so located that immediately after the heat transfer elements leave the gas passage of the preheater they align with the primary air outlet before turning further into position to align with the secondary air outlet.

In carrying out the present invention, sector plates of the usual form are provided at each end of the housing, i. e. each sector plate has an opening for gas and a single opening for air, these openings being separated by a diametrically extending imperforate portion of the sector plate. In accordance with the invention the air outlet opening of the preheater is provided with wedge shaped shutter movable to divide it into two parts, one for primary and one for secondary air. By movement of the shutter away from or toward the edge of the air opening nearest the gas passage of the preheater, the size of the outlet opening for primary air may be enlarged or diminished. Depending upon the adjustment of the movable shutter, air passing to the primary air duct traverses a greater or lesser cross-sectional area of the heating surface at the air side of the preheater and is correspondingly heated.

A further feature of the invention is that when it is desired to lower the temperature of the primary air below the maximum obtainable from the preheater at a certain load this may be effected by adjusting the shutter so that the volume of primary air traverses a smaller amount of heat transfer surface. This avoids mixing cool air with the heated primary air to temper it and

thus eliminates varying the load of the air fan or fans.

In the accompanying drawings:

Figure 1 is a sectional elevation of a rotary regenerative air preheater embodying the present invention;

Figure 2 is a sectional view on the line 2—2 in Figure 1 affording a plan view of the sector plate at the air outlet end of the preheater together with the adjustable wedge-shaped shutter provided for regulating the size of the primary air outlet opening;

Figure 3 shows on an enlarged scale that part of Figure 2 illustrating the adjustable shutter and the operating mechanism therefor;

Figures 4 and 5 are sectional views taken along the correspondingly numbered section lines in Figure 2 or 3 and illustrate the mounting devices and operating mechanism for the adjustable shutter; and

Figure 6 is an enlarged sectional view on line 6—6 of Figure 4 of a sealing device associated with the adjustable shutter.

The air preheater shown in Figure 1 is of the familiar rotary regenerative type according to Ljungstrom Patent No. 1,522,825, issued January 13, 1925; it has a stationary housing 10 within which is mounted a cylindrical rotor 11 divided by radial partitions or diaphragms 12 into a plurality of sector-shaped compartments each containing regenerative heat transfer surface in the form of undulated or corrugated metallic plate 13. These plates first absorb heat from hot gases when moving through the gas side of the preheater and then impart the heat to air in travelling through the air side of the preheater as the rotor is turned slowly about its axis 14 in a clockwise direction (Fig. 2) by a motor (not shown) operating through suitable reduction gearing.

40 The outlet duct for gas is designated 16 in Fig. 1 and the inlet and outlet ducts for air are numbered 17, 18 respectively.

At each end of the housing opposite the rotor 11 is a sector plate (Fig. 2) designated as a whole by the numeral 29. It consists of an annulus 21 with a diametrical web providing two large openings 24 and 25 separated by the imperforate radial web portions 26 and defining the gas and air passages of the preheater. The radial partitions 12 are provided with radial seals 23 adapted as the rotor turns to bear against the imperforate portions 26 of the sector plates 29 to prevent the flow of fluids across the ends of the rotor between the gas and air passages of the preheater, the web portions 26 being of greater width than the

arcs subtended by the various sector-shaped compartments into which the rotor is divided by the partitions. The construction described above is conventional.

The preheater shown herein has a special outlet conduit 30 for primary air in addition to the outlet conduit 31 for secondary air, both merging with the usual air outlet duct 18 as appears in Fig. 1. According to the present invention there is mounted in the air outlet opening 25 in the lower sector plate 20 an adjustable shutter 32. The shutter is shaped at its inner edge to conform to the part 27 of the imperforate web 26 that rings the rotor post 14 and at its outer end to the curvature of the inner radius of the annular section 21 of the sector plate that defines one side of the air outlet 25. As appears in Figure 5, arc shaped ledges 33 are provided adjacent the outer and inner edges of the air opening 25 at the end thereof where the plates 13 first emerge from the gas passage. The ledges 33 serve as guide tracks on which the end edges of depending flange portions 34 of shutter 32 ride. The flanges 34 carry toothed racks 40, 41 engaging with gears 42, 43 carried by a radially disposed shaft 44 suitably journaled within the duct 18 just beyond one end of the ledges 33 that support shutter 32. Meshing with the gear 43 is a pinion 45 fixed to a stub shaft extending through the outer wall of the duct 18 and provided with a lever 46 operable to drive the gears 42, 43 and move the shutter 32 away from or toward the edge 36 of air passage 25 for increasing or decreasing the size of the opening 37 opposite the primary air conduit 40. A latch 47 (Fig. 4) engageable with a notched sector 48 is provided to hold shutter 32 in its adjusted position.

Extending upwardly from the juncture 50 (Fig. 1) of the primary air conduit 30 and secondary air conduit 31 is a partition 51 subdividing the interior of air outlet duct 18 immediately below the lower sector plate 20 to direct the air from the primary air opening 37 into the primary air conduit 30 and the air from the remaining section 38 of air passage 25 into the secondary air conduit 31. The lower part 52 of partition 51 is sloped to meet the inner side of conduit 30. The upper portion 53 of partition 51 extends radially and is provided with a radial seal 54 in contact with the underside of the movable shutter 32 so as to prevent cross flow of primary and secondary air.

In operation dampers 55, 56 in the primary and secondary air ducts are adjusted to apportion the total volume of air flowing through the preheater between the furnace connected to the secondary air duct 31 and the fuel drying mill or other apparatus to which duct 30 leads. The further away the shutter 32 is positioned from the edge 36 of opening 25 the greater will be the size of the primary air opening 37 and the amount of heat transfer surface in the direct path of primary air. Thus as the size of opening 37 is increased, the temperature of the volume of primary air as determined by the adjustment of dampers 55, 56 is raised. When the shutter 32 is moved counterclockwise reducing the size of opening 37 the resistance created by obscuring the lower end of passages between plates 13 above the shutter causes substantially the entire volume of primary air to follow the path of least resistance and traverse passages between plates 13 registering with opening 37. As a result of traversing a small amount of heat transfer surface the primary air is less intensely

heated. The dampers 55 and 56 are provided so that upon movement of shutter 32 to regulate the temperature of the primary air the same relative volume of primary air may be obtained by adjusting them to compensate for decreased or increased resistance through the primary air section of the rotor as the shutter is opened to increase or to decrease the primary air temperature.

What is claimed is:

1. In regenerative heat exchange apparatus having passages for a heating gas and air or other gaseous fluid to be heated, ducts for supplying hot gas and relatively cool air thereto, and a rotor carrying regenerative material adapted to be moved first through the gas passage for absorbing heat from the gases flowing therethrough and then into the air passage to impart heat to the air flowing therethrough; a sector plate at the air outlet end of the preheater having an opening opposite the end of the rotor for the discharge of heated air; an offtake conduit communicating with a determined portion of said air outlet opening that is located adjacent the point of entrance of the heated regenerative material into the air passage during rotor movement; means for regulating the volume of air flowing through the rotor into said conduit; a movable, imperforate shutter disposed intermediate the air outlet end of said rotor and said outlet conduit to partially obscure the portion of said end of said rotor that communicates with said conduit so as to concentrate the flow of air through the unobscured section of the rotor registering with said portion of the opening in said sector plate; and means for adjustably positioning said shutter.

2. In regenerative heat exchange apparatus having passages for a heating gas and air or other gaseous fluid to be heated, ducts for supplying hot gas and relatively cool air thereto, and a rotor carrying regenerative material adapted to be moved first through the gas passage for absorbing heat from the gases flowing therethrough and then into the air passage to impart heat to the air flowing therethrough; a sector plate at the air outlet end of the preheater having an opening for the discharge of heated air; an air offtake conduit communicating with a determined portion of said air outlet opening that is located adjacent the point of entrance of the heated regenerative material into the air passage during rotor movement; means for regulating the volume of air flowing through said conduit; an adjustable, imperforate shutter disposed opposite the outlet end of said rotor in the air outlet opening in said sector plate for varying the free area of the part of said opening registering with said rotor and communicating with said primary air conduit; and means for adjustably positioning said shutter.

3. In regenerative heat exchange apparatus having passages for a heating gas and air or other gaseous fluid to be heated, ducts for supplying hot gas and relatively cool air thereto, and a rotor carrying regenerative material adapted to be moved first through the gas passage for absorbing heat from the gases flowing therethrough and then into the air passage to impart heat to the air flowing therethrough; a sector plate at the air outlet end of the preheater having an opening opposite the end of the rotor for the discharge of heated air; a primary air conduit communicating with a determined portion of said air outlet opening that is located adjacent the

point of entrance of the heated regenerative material into the air passage during rotor movement; a secondary air conduit located beyond said primary air conduit in the direction of rotor movement and communicating with the remainder of said air outlet opening; damper means in said conduits for apportioning between them the volume of air flowing through the air passage; a movable, imperforate shutter disposed opposite the end of said rotor intermediate it and said primary air conduit and partially obscuring the portion of the opening in said sector plate that communicates with said primary air conduit so as to reduce the area of the part of said opening affording free flow of air between the rotor and said conduit; and means for moving said shutter to vary the area of said portion of the air outlet opening that affords free flow between said rotor and conduit.

4. In regenerative heat exchange apparatus having passages for a heating gas and air or other gaseous fluid to be heated, ducts for supplying hot gas and relatively cool air thereto, and a rotor carrying regenerative material adapted to be moved first through the gas passage for absorbing heat from the gases flowing therethrough and then into the air passage to impart heat to the air flowing therethrough; a sector plate at the air outlet end of the preheater having an opening opposite the end of the rotor for the discharge of heated air; a partition associated with said sector plate acting to set off a portion of predetermined area, adjacent the point of entrance of said rotor into the air passage, from the remainder of said air outlet opening; an off-take conduit communicating with said portion of the outlet opening; a movable, imperforate shut-

ter disposed between the end of said rotor and said partition for partially obscuring said portion of said outlet opening to concentrate the flow of air through the section of the rotor registering with the unobscured part thereof; sealing means carried by said partition and bearing against said shutter; and means for adjustably positioning said shutter.

5. In regenerative heat exchange apparatus having passages for a heating gas and air or other gaseous fluid to be heated, ducts for supplying hot gas and relatively cool air thereto, and a rotor carrying regenerative material adapted to be moved first through the gas passage for absorbing heat from the gases flowing therethrough and then into the air passage to impart heat to the air flowing therethrough; a sector plate at the air outlet end of the preheater having an opening opposite the end of said rotor for the discharge of heated air; partition means associated with said sector plate acting to set off a portion of predetermined area, adjacent the point of entrance of said rotor into the air passage, from the remainder of said air outlet opening; an off-take conduit communicating with said portion of said outlet opening; a movable, imperforate shutter disposed between the end of said rotor and said partition for partially obscuring said portion of said outlet opening to concentrate the flow of air through the section of the rotor registering with the obscured part thereof; means for adjustably positioning said shutter; and sealing means carried by said partition and bearing against said shutter to prevent leakage of air to or from said portion of said air outlet opening in various positions of said shutter.
